PAPER CARTRIDGE AND METHOD OF AND
MEANS FOR TREATMENT THEREOF

Hobson F. Miller, Oceanside, N. Y.

No Drawing. Application June 27, 1934,
Serial No. 732,665

4 Claims. (Cl. 91—68)

This invention relates to means and a method for treating the exposed edges of rolls or stacks of paper, for the purpose of improving the quality and handling characteristics of the paper taken from such stack, or drawn from such roll, in printing, perforating, stacking and punching operations performed by various kinds of machinery adapted for those purposes; and to the roll or stack of paper so treated as a new article of manufacture.

The description which follows relates to a specific application of the invention, namely, the treatment of rolls of paper which are to be used in bill-form printing machines of the type which draw a continuous web of paper from a feed roll, and print legends and figures thereon, address the same, and perforate, number, cut off and stack individual customer's bills in condition for placing in envelopes and mailing. Such machines, in common use today, turn out many thousand individual customer's bills per day, and require a paper feed of as nearly as possible uniform quality and handling characteristics.

Among the difficulties which have heretofore been met with are that the paper at times has a tendency to curl as it passes through the machine which interferes with the printing, cutting and other operations therein, and with the stacking of the severed sections which are delivered by the machine; that at certain times the paper acquires a considerable charge of static and in consequence thereof the severed portions, as they are delivered by the machine, are difficult to handle and have a tendency to adhere to each other or to parts of the machine; that welts sometimes form on the ends of the paper roll, forming humps on the side of the web of the paper which tend to catch on the guides and to stop the feed of the paper or cause tearing thereof; and that the normal deposit of "lint" on the cut edges of the paper, necessarily produced by cutting knives in the paper mill, tends to collect in the printing machine and there to become mixed with dust and oil tending to clog the mechanism and the type face, and to thicken the ink, requiring frequent stoppage of the machine for cleaning purposes. These difficulties are inherent and recognized problems in the operation of high speed bill-form printing machines, and so far as I am aware no satisfactory method has heretofore been devised for minimizing or overcoming them.

Among the objects of the present invention are to provide means and a method for treating rolls or stacks of paper as they come from the

cutting machinery, for reducing in large measure the tendency of the paper to curl under adverse conditions of temperature and humidity, for reducing in large measure the tendency of welts or humps to form on the ends of the paper roll under the same conditions, for reducing in large measure the formation of static charges in the paper causing it to become unmanageable, and for eliminating entirely the accumulation of lint in the printing machinery in which the paper is employed.

In large size bill-form printing machines rolls of paper are mounted within the machine for rotation therein, and a continuous web is drawn therefrom between guides. In one type of such machine, which may be used for purposes of illustration, the roll is 17 inches in length and the web of paper drawn therefrom is 17 inches wide. Sufficient paper is contained in the roll to permit operation of the machine at full speed for twenty-four hours. Such rolls are formed in the paper mill by re-rolling strips of paper formed by slitting strips of much greater width. The slitting operation leaves a residue of "lint" on the edges of these strips and on the ends of the 17-inch rolls, this lint being an accumulation of paper fragments or fibre produced by the cutting or slitting knives. Necessarily, also, the exposed edges of the paper at each end of the 17-inch roll present unprotected paper fibres to the atmosphere, without the protection of the normal surface sizing.

In the ordinary roll of paper as now furnished by paper mills for the bill-form printing machines, the various edges of the paper do not all lie in exactly the same plane at the end of the roll. Some slight irregularity is necessarily produced in the machines which roll the paper at the mill. Thus certain layers of paper project outwardly beyond others, and these projecting layers become sources of additional lint because of the fraying which occurs when the rolls are handled.

I have found that such rolls are highly sensitive to atmospheric conditions of humidity and that the tendency of the paper to become unmanageable in the printing machine (either by curling, change in size, raising of welts on the ends, or accumulation of static charges) is in part at least traceable to the facility with which atmospheric moisture may penetrate the fibres of the paper through the exposed ends thereof, or contained moisture within the fibres may evaporate to the atmosphere.

According to the preferred form of the present

55

invention each end of a roll of paper of a size suitable for use in a bill-form printing machine is first treated, by spraying, painting or otherwise applying, with a liquid sealing material sufficiently fluid in character to be adapted to penetrate the paper fibres in the exposed edges of the sheets at the end of the roll, and having the property of hardening or drying within the fibres into a relatively hard moisture-resisting solid. Such liquid sealing materials include shellac, varnish, lacquer, starch sizing, animal sizing (glue), resin sizing, or aluminum paint, either with or without the addition of a pigment. Of the substances named, I prefer, however, to use shellac, which appears to give the most satisfactory results. The liquid sealing material penetrates the edges of the paper and impregnates the fibres thereof to an extent sufficient, upon drying or hardening, to make an effective seal, tending to prevent rapid absorption or giving off of moisture by the fibres within the paper. Sufficient liquid is applied to penetrate the edges of the paper to a depth sufficient to maintain an effective seal after a portion of the surface of the end of the roll has thereafter been removed, as set forth below. Penetration to a depth of one-eighth of an inch will ordinarily be sufficient for this purpose. In this form of the invention if some excess remains, no harm is done since it will be removed in the succeeding steps of treatment.

When the sealing material applied to the end of the roll has dried or hardened, the ends of the roll are then abraded or polished by means of fine sand-paper, or a carborundum polishing machine, or fine emery cloth until a smooth surface is obtained. It is desirable that this operation be carried far enough so that all projecting layers of paper are leveled off, and irregularities in the surface of the end of the roll are eliminated. Ordinarily about one-sixteenth to one thirty-second of an inch of paper, in the average sheet, is removed by the abrasive, but the amount of paper removed by the abrasive should be insufficient to expose paper fibres which have not been impregnated by the sealing material previously applied. Then the ends of the roll are wiped or brushed, and may in addition be further cleaned by means of a vacuum- or suction-cleaning device.

Thus, in the preferred form of the invention, the initially fluid character of the sealing substance applied is made use of to assure a deposit within the paper fibres of a hard sealing substance to a depth below the average level of the edge of the roll sufficient to assure that the subsequent removal of a portion of that surface by abrasion will not break the seal formed within the paper fibres at the edge of each sheet.

When the roll has been treated in the preferred manner above described, I have found that each of the difficulties heretofore ordinarily experienced with the handling qualities of the paper in a bill-form printing machine is overcome to a pronounced degree. Paper drawn from a roll so treated has a markedly reduced tendency to curl in the printing machine, and a markedly reduced tendency to accumulate a charge of static. Furthermore, the tendency for welts or humps to form on the end of the roll in damp weather is substantially reduced and nearly eliminated. Finally, I have found that the accumulation of lint in the printing machine, which is a characteristic of all such machines heretofore used, has been completely eliminated, and such machines may be run for long periods without the appearance of any lint and without clogging of the type or

thickening of the ink or other attendant disadvantages. Nor does the sealing material cause the sheets to stick together.

By first applying the sealing liquid or material to the end of the roll as it comes from the mill, and then removing excess sealing material, paper fibres and lint by the subsequent abrading or polishing steps of the process, rolls of an exact length can be manufactured and, when so made, will be substantially free of subsequent tendency to shrink, expand, curl, or accumulate charges of static due to changes in atmospheric humidity. Such sequence of steps therefor constitutes the preferred form or embodiment of this invention.

However, by changing the order of steps as set forth below, many of the advantages above described can also be obtained. For example, if the abrading or polishing and cleaning steps are first employed on the end of the rough roll as it comes from the mill, a smooth surface is obtained to which the liquid sealing material above described may then be applied. Paper which has been treated in this manner will be noticeably improved in respect to its tendency to curl, change in size, form welts and accumulate a charge of static, and if care is taken not to apply an excess of liquid sealing material to the end of the roll the sheets will not stick together nor tear in the printing machine. While the accumulation of lint in a printing machine from paper rolls treated in this manner is also greatly reduced, it is my present belief that somewhat better results in this respect are obtained when the rough roll is first treated with a sealing material and afterwards polished as in the preferred form described above.

According to this alternate form of my invention, therefore, the ends of the rough rolls as they come from the cutting machinery at the mill, are first abraded or polished by any of the means above described till a smooth surface is obtained. As much paper may be removed as desired, preferably until the length of the roll has been exactly established at the desired dimensions. Then the ends may be wiped or brushed or vacuum-cleaned.

To the end of the roll, as so prepared, is then applied, by spraying, painting or otherwise, a suitable sealing material which may be one of the liquid sealing materials mentioned above, or any other material capable of making an effective seal in or on the edges of the paper without causing these edges to stick together and without itself having sufficient body to flake off and have a detrimental effect comparable to that of lint. In applying such a substance, care must be exercised to avoid applying an excess thereof, lest the sheets adhere to each other and tear in the printing machine, and lest the excess tend to flake and clog the printing machinery.

According to a third form of my invention, the rough ends of the rolls as they come from the cutting machinery at the paper mill, are not subjected to an abrading or polishing or cleaning step, but the sealing material, as described above, is applied in the manner stated, taking care to avoid such excess thereof as will cause adjacent sheets of paper to stick together and cause tearing. This form of the invention does not accomplish elimination or reduction of lint, but it realizes each of the other advantages hereinabove set forth and is useful where lint is no objection but where it is desired to reduce static, curling tendency, change of size, shrinkage, and other objectionable characteristics of the paper prob-

ably due to changes arising from atmospheric humidity.

It is my present belief and understanding that my invention is applicable either to rolls or to 5 stacks of paper (referred to generally as a "cartridge" in the annexed claims) and wherever it is desired to reduce the tendency of the sheets to curl or distort or collect a charge of static, because of changes in the moisture content. It is 10 my understanding that these advantages may also be usefully attained where lint formation is unimportant. For these reasons my invention is herein set forth in three forms or modifications. It will be understood however that the first or 15 preferred form of the invention as herein described, has its most particular field of usefulness in connection with bill-forming machines of the character described where the conditions are such that it is important not only to control curling, welling and static accumulation, but also to prevent the formation of lint.

While I have named above all of the seal forming substances now known to me as being adaptable to give satisfactory results in the practice 25 of my invention, and have indicated my belief that, of those named, shellac is the best, it is my intention and purpose to assert that other comparable and equivalent substances having properties enabling them to function in the same 30 manner, and to produce the same result, shall be regarded as within the scope of my invention, as defined in the claims which follow.

I claim:

1. In the art of preparing a paper roll for use 35 in high speed web printing machinery, the steps

of coating both ends of the roll with a penetrating liquid which hardens to a moisture-resisting solid, and abrading the hardened coating to remove excess coating material without exposing paper fibers which have not been impregnated 5 with said liquid.

2. In the art of preparing a paper roll for use in high speed web printing machinery, the steps of applying to both ends of the roll a sealing material sufficiently fluid in character to impregnate 10 the paper at the edges thereof exposed at the ends of said roll and adapted to harden therein to form a moisture-resisting solid, and removing a portion of the impregnated paper at each end of the roll sufficient to remove excess sealing 15 material without exposing portions of the paper which have not been impregnated with said sealing material.

3. In the art of preparing a paper roll for use in high speed web printing machinery, the 20 steps of applying to both ends of the roll a sealing material sufficiently fluid in character to impregnate the paper at the edges thereof exposed at the ends of said roll and adapted to harden 25 therein to form a moisture-resisting solid, and removing a portion of the impregnated paper at each end of the roll sufficient to remove excess sealing material and projecting portions of the paper so as to establish a smooth surface free 30 from lint without exposing portions of the paper which have not been impregnated with said sealing material.

4. A process according to claim 2 wherein the said removal is effected by abrasion.
